UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 18, 1923, Serial No. 652,224. Renewed August 30, 1924.

This invention relates to manifolding typewriting machines of the continuous billing type in which a composite sheet or web is fed around a cylindrical platen, the web comprising several plies of work-sheets having successive corresponding forms printed thereon, said plies being sometimes separated from each other and sometimes joined at their side edges to form a fan-fold web, the various plies having carbon-sheets interleaved therebetween which are displaceable at intervals along the web to fresh sets of untyped forms. The invention relates more particularly to means to facilitate the relative displacing or shifting between the carbon-sheets and the work-sheets.

One form of this kind of machine is disclosed in the patent to Wernery & Smith, No. 1,132,055, dated March 16, 1915. In said machine the platen is mounted in a swing frame by which it may be displaced upwardly from its normal typing position, so that that portion of the web containing the carbon-sheets may be straightened out preparatory to a carbon-displacing operation.

Another form of machine for handling this kind of work is disclosed in the application of Jesse A. B. Smith, Serial No. 640,815, filed May 21, 1923, in which there is provided means to so condition the web that there may be a relative shifting between the carbon-sheets and the work-sheets without lifting the platen, the platen remaining always in its usual typing position. To this end there is provided in said Smith machine a curved table at the rear of the platen over which the web is conducted and from which it extends tangentially to the platen, when said table occupies its effective position. Said table is pivoted at one end nearest the platen and may be swung from a normally ineffective position to an effective position where the web may be stretched over said table, at which time the work-sheets may be fed forwardly to shift them while the carbon-sheets are held.

An object of the present invention is to provide a curved table with a relatively fixed platen, said table being rotatable about its axis to move it from an ineffective position to an effective position, and being effective while it is being rotated to withdraw the web around the platen to free the

carbon-sheets from the platen while the feed-rolls are released.

After the carbon-sheets have been freed from the platen, the table is held in its effective position while the work-sheets are advanced around the platen to shift them relatively to the carbon-sheets, a suitable gage being provided at the delivery side of the platen to which the leading edges of the typed forms are brought to determine the extent of shifting movement of the work-sheets. The table may then be rotated to its lowermost position, and the web may then be fed to bring the leading edges of the work-sheets to a second gage, thus bringing the carbon-sheets to the printing point and the bottoms of the typed forms to a knife where they may be severed, the fresh set of forms being in readiness for typing the first line.

It will be understood that by mounting the table at its axis, it may be kept above the bottom limits of the main frame of the machine, so that it may be set on a flat table with the typewriting machine.

Other features and advantages will hereinafter appear.

In the accompanying drawings,

Figure 1 is a part sectional side view of an Underwood typewriting machine, showing the invention applied thereto, the parts being in a typing position.

Figure 2 is a top plan view of the machine with the parts in Figure 1 position.

Figure 3 is a view similar to Figure 1, but shows the web-conditioning table rotated to its raised position to withdraw the web around the platen and free the carbon-sheets from the platen, the feed-rolls having previously been released.

Figure 4 is a view similar to Figure 3 with some of the parts omitted, the parts occupying the same position as in Figure 3, except that the feed-rollers have been thrown on to advance the work-sheets to the first gage while the carbons are held.

Figure 5 is a view similar to Figure 3 and shows the table returned to its lower position and the web advanced to the second gage bringing the carbon-sheets to typing position, and the bottoms of the type forms to the knife.

Type-bars 10 strike against the front of a revoluble platen 11, which is journaled in the usual manner in a platen-frame compris-

ing ends 12 and a rear paper-shelf 13. The usual front and rear feed-rolls 14 run on the under side of the platen. They may be released, or thrown from the platen, by 5 means of a finger-piece 15, connected by a link 16 to an arm 17, fast on a shaft 18. The shaft 18 is provided with flats, against which arms 19, forming part of levers 20, are held by spring-pressure. The levers 10 20 are pivoted on a shaft 21, so that, when the finger-piece 15 is actuated, and the arms 19 spread apart by turning of the shaft 18, the levers 20, which support the pressure-rolls, are rocked on the shaft 21 to 15 release the rolls. This roll-releasing structure is that commonly found in the standard Underwood typewriting machine.

The work-web, usually comprising superposed plies 22 (which may be separate or 20 which may form a fan-fold), is drawn up from a supply-spool, or from a zigzag folded pile (not shown), but which may be contained in a receptacle arranged in the rear of the typewriting machine and its stand 23. 25 As the plies of the work-web rise from the supply at 24, they first pass through a carbon-holder 25; and are there interleaved with the carbons 26. Each of the carbons 26 has its rear end attached to one of two 30 blades 27, carried by standards 28 on the ends of a plate 29. The plate 29 is secured to a bar 30, forming the rear reach or cross-tie of a frame which is secured to, and travels with, the platen-carriage 31. The ends 35 32 of the bar 30 are offset to form ears, which are secured by rivets or screws 33 to the side pieces 34 of this traveling frame. At their front ends, the side pieces 34 have offset ears 35, to which is secured, by screws 40 or rivets 36, a bar 37, which ties together the side pieces 34 at the forward end of the traveling frame. The front cross tie or bar 37 is secured by screws or rivets 38 to brackets 39, in turn, secured by screws or rivets 45 40 to the usual rear cross piece or tie 41 of the platen-carriage 31. The platen-carriage rides in the usual manner on a rail 42 on the main frame 43 of the machine; the main frame resting directly, as shown in Figure 50 1, upon the table or support 23. For supporting the carbon-carrier traveling frame on the table 23, for movement with the platen-carriage in letter-feed and return directions, the table 23 is provided at its rear 55 with a rail 44, on which ride rollers 45, journaled in brackets 46, depending from, and secured by screws or rivets 47 to, the rear cross-bar 30 of the traveling frame. The brackets 46 are offset at their lower 60 ends at 48 under the rail 44, to serve as guards for holding the traveling frame to the support 23.

When the parts are in typing position, the work-plies 22, interleaved with the carbons 26, pass upward from the carbon-

holder over a roller 49, and thence forward to and over a roller 50, journaled at 51 in the side plates 34 of the traveling frame, above and at the rear of the paper table 13; the roller 50 being so located that the composite web may pass tangentially therefrom, down over the table 13 to the rear under-face of the platen, whence it is guided around the platen, up across the printing line, and along and in front of a staff 52, 75 to which is adjustably secured, by means of a set-screw 53, a gage 54, the purpose of which gage will hereinafter more fully appear. Between the rear roll 49 and the front roll 50 the composite web is in the 80 form of a slack 55, which is sufficient to permit of line-space feed of the composite web with the platen, in the typing operation, without complete elimination of the slack before the typing operation itself is completed.

After typing on a form-section of the composite web is completed, the feed-rolls 14 are released, and the composite web as a unit is withdrawn rearward around the platen until it assumes the position shown in Figure 3, wherein the leading ends of the carbons are shown as having been cleared from the platen. This rearward withdrawal of the composite web, to free the carbons from the platen, is effected by means of a table 56, which is of long arcuate formation, and which is secured by screws or rivets 57 to ears 58 on the arms 59, 60 and 61 of a spider or standard, pivoted at 62, for rotary movement on the side plates 34 of the traveling carbon-holder frame. It will be understood, from Figure 2, that there are two sets of arms 59, 60 and 61, one set at each side of the arcuate table 56, so that the latter with its supporting arms is, in effect, a section of a drum or cylinder, journaled at its ends in the side plates 34 of the traveling frame, so as to have movement with the platen-carriage in letter-feed and return directions with such traveling frame. The roller 49, over which the composite web first passes, as shown in Figure 1, after leaving the carbon-holder, is journaled at 62^a in the arms 59 of the rotary table; and the arms 59, 60 and 61 serve as guards, between which the side edges of the slack portion 55 of the web, in Figure 1 position of the latter, is held during the travel of the platen-carriage. It will also be noted that the convexity of the table 56, in its Figure 1 position, provides space for the slack 55. The Figure 1 position of the table is determined by engagement of the right-hand arm 61 of the rotary table with a pin 63 on the right-hand side piece 34 of the traveling carbon-holder frame.

For rotating the table 56 from Figure 1 to Figure 3 position, to release the carbons from the platen, there is provided a handle 130

64, which is unitary with a rack 65, and which is pivoted at 66 to the left-hand side plate 34 of the traveling carbon-holder frame. The rack 65 meshes with a pinion 67, journaled at 68 to the same side piece 34; and the pinion 67, in turn, meshes with a pinion 69, fast on a stub-shaft 70, which forms the left-hand journal of the table 56, and to which the table 56 is made fast. 5 Suitable collars 71 on the journals 70 and 72 of the table 56 serve to hold the latter properly spaced between the side plates 34 of the traveling carbon-holder frame. It follows from the above that, when the operating arm 64 is drawn forward, from Figure 1 to Figure 3 position, the table 56, by means of the rack 65, pinion 67, and pinion 69, is swung clockwise, looking from the left, from Figure 1 to Figure 3 position. 10 The table 56 is arrested in its Figure 3 position by the engagement of a stop-pin 73 on the right-hand arm 59 of the table 56 with the end 74 of an ear 75 on the right-hand side plate 34 of the traveling carbon-holder frame. 15

During the throw of the table 56 to Figure 3 position, the roller 49 serves as an anti-friction device for drawing out the web, without injury to the latter, and without 20 tearing the carbons from their anchorage on the blades 27 of the carbon-holder. In Figure 3 position of the table, it will be noted that the carbons and work-webs lie smoothly on the table 56, so that subsequent 25 shift of the work-webs forward with respect to the carbons, to clear the typed forms of the webs from the carbons, and to pass the carbons to the next untyped forms, may be effected without crumpling or injury to either the carbons or the work-plies. In this 30 connection, it will be noted that, during the movement to the Figure 3 position, the composite web is at all times tangential to the table at the rear of the latter; and that, when in Figure 3 position, the web extends 35 tangentially from the forward end of the table to the platen. All sharp bends, such as might injure the same, are thereby avoided. 40

With the parts in Figure 3 position, the aforesaid forward shift of the work-webs with respect to the carbons is effected by first reapplying the feed-rolls 14, and then turning the platen by one of the usual hand-knobs. During this operation, the handle 45 64 is held by the operator in its forward Figure 3 position, so as to prevent movement of the table 56; and the carbons, being held by the carbon-holder and being in taut condition, cannot be advanced with the web. The lower end 76 (see Figure 4) of an arm 50 77, unitary with the gage 54, serves as a gage for determining, by registration therewith of the leading ends of the work-webs, the amount of advance of the work-webs 55

sufficient to properly position the carbons in the next untyped form-sections of the work-webs.

It remains then to advance the composite web to a position for detachment of the 70 leading typed form-section thereof, and to position the next untyped form-section for commencement of typing. It is for this purpose that the gage 54 is provided, as shown in Figure 5. The movement of the 75 composite web to bring the leading ends of the work-webs to the gage 54 is effected by a further forward rotary movement of the platen. Preliminary to such further forward rotary movement of the platen, and for the reason that the carbons must advance with the work-plies during such movement, the handle 64 must be thrown to Figure 1 position, to return the table 56 to Figure 1 position, so that a slack 55 will be 80 re-established in the web-plies and carbons. Such re-established slack will be not only sufficient to permit advance of the carbons from Figure 4 to Figure 5 position, but will also be sufficient to take care of the subsequent line-space feed of the carbons as part of the composite web in the typing of the next form. To prevent catching of the web on the table 56, in its return to Figure 1 position, the rear edge 56a of the same may 85 be curved inward. 90

When the leading edges of the leading typed form register with the gage 54, the rear edges of the leading typed form register with the cutting edge of a blade 78, so 100 that, as indicated in Figure 5, the typed form-section may be severed from the rest of the web by drawing the web against the blade. The blade 78, as shown in Figure 2, is secured by rivets or screws 79 to brackets 80, in turn, secured by screws or rivets 81 to the end pieces 12 of the platen-frame. The brackets 80 also serve to support a cross-plate 82, to which the gage-staff 52 is centrally secured at 83. After detachment of 105 the typed form-section, as indicated in Figure 5, or without detaching such form-section, typing on the next form may be commenced. 110

For guiding the web into properly centered position on the platen, side gages or plates 84, offset from clips 85, are adjustably and removably secured to the paper-table 13 by springing the curved ends of the 120 clips 85 over the rolled upper edge of the table 13. 115

It will be noted, on reference to Figures 1 and 3, that in all positions of the rotary table or shell 56, the same is above the platform 23 which supports the machine, so that the platform may be extended horizontally rearward to the support thereon for the sub-carriage or traveling carbon-holder frame. It will also be noted that no space 125 between the rotary table or shell and the 130

machine, or at the rear of the table or rotary shell, is required for the slack in the web; the concavity of the table or shell itself providing the space for the slack. Since the table or shell in its carbon-releasing position requires no more space to the rear of the machine than in its normal or typing position, and since the means for rotating the shell may, in effect, be located within the shell or space which the latter occupies; and since the web may be led directly and vertically up onto the end of the rotary table, the whole presents an extremely compact structure, requiring no space below the machine-platform, and requiring a space only slightly greater than the diameter of the shell at the rear of the machine.

Variations may be resorted to within the scope of the invention, and portions of the improvements may be used without others.

Having thus described my invention, I claim:

1. In a continuous billing typewriting machine, the combination of a carriage, a platen on the carriage, around which a composite web comprising plies of work-sheets may be fed with interleaved carbon-sheets, a sub-carriage to travel with the platen-carriage, and a revolute device pivoted at an intermediate point thereof to the sub-carriage for rotation against the web, to draw the carbon-sheets clear of the platen to condition the web for a relative shift of the carbon-sheets and work-sheets.

2. In a continuous billing typewriting machine, the combination of a carriage, a platen on the carriage, around which a composite web comprising plies of work-sheets may be fed with interleaved carbon-sheets, a sub-carriage to travel with the platen-carriage, and a revolute curved table pivoted at an intermediate point thereof to the sub-carriage for rotation against the web, to draw the carbon-sheets clear of the platen to condition the web for a relative shift of the carbon-sheets and work-sheets.

3. In a continuous billing typewriting machine, the combination of a carriage, a platen on the carriage, around which a composite web comprising plies of work-sheets may be fed with interleaved carbon-sheets, a sub-carriage to travel with the platen-carriage, and a revolute curved table pivoted at an intermediate point thereof to the sub-carriage behind the platen-carriage for rotation against the web, to draw the carbon-sheets clear of the platen to condition the web for a relative shift of the carbon-sheets and work-sheets.

4. In a continuous billing typewriting machine, the combination of a carriage, a platen on the carriage, around which a composite web comprising plies of work-sheets may be fed with interleaved carbon-sheets, a sub-carriage to travel with the platen-

carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, and means for directing the web tangentially onto and off of the table when the latter is in carbon-releasing position.

5. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, and a guide on the table for the web when the table is in its normal or typing position.

6. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, and a roller on the table, over which the web is guided when the table is in its normal or typing position.

7. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, a roller on the table, over which the web is guided when the table is in its normal or typing position, and another roller near the front of the table for directing the web down and under the platen.

8. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage be-

- revoluble table entirely above the platform, and means for guiding the web vertically onto the end of the table when the latter is in its normal or typing position.
- 5 16. In a continuous billing typewriting machine, the combination of a carriage, a platen on the carriage, around which a composite web comprising plies of work-sheets may be fed with interleaved carbon-sheets, a 10 sub-carriage to travel with the platen-carriage, a revoluble, invertible, concavo-convex table pivoted upon the sub-carriage and having a normal or typing position in which a slack in the web hangs in the 15 cavity of the table, means for rotating the convex surface of the table against the web to draw the carbon-sheets free of the platen and eliminate the slack in the web, a platform for the machine, means for supporting 20 the revoluble table entirely above the platform, and means above the forward end of the table, when the latter is in its normal or typing position, for directing the web down under the platen.
- 25 17. In a continuous billing typewriting machine, the combination of a carriage, a platen on the carriage, around which a composite web comprising plies of work-sheets may be fed with interleaved carbon-sheets, a 30 sub-carriage to travel with the platen-carriage, a platform for the machine, a curved table pivotally supported upon the sub-carriage and in all positions thereof above the platform, and means for rotating the curved table against the web to draw the carbon-sheets free of the platen.
- 35 18. In a continuous billing typewriting machine, the combination of a carriage, a platen on the carriage, around which a composite web comprising plies of work-sheets may be fed with interleaved carbon-sheets, a 40 sub-carriage to travel with the platen-carriage, a revoluble curved table pivoted on the sub-carriage at the rear of the platen-carriage, a gear on the axis of the table, and driving gearing on the sub-carriage, intermediate the platen-carriage and said first-mentioned gear, for rotating the table against the web to free the carbon-sheets 45 from the platen.
- 50 19. In a continuous billing typewriting machine, the combination of a carriage, a platen on the carriage, around which a composite web comprising plies of work-sheets may be fed with interleaved carbon-sheets, a 55 sub-carriage to travel with the platen-carriage, a revoluble curved table pivoted on the sub-carriage at the rear of the platen-carriage, a gear on the axis of the table, and driving gearing on the sub-carriage, intermediate the platen-carriage and said first-mentioned gear, for rotating the table against the web to free the carbon-sheets 60 from the platen, said driving gearing comprising a rack and a handle for swinging the rack.
- 65 20. In a continuous billing typewriting machine, the combination of a carriage, a platen on the carriage, around which a composite web comprising plies of work-sheets may be fed with interleaved carbon-sheets, a sub-carriage to travel with the platen-carriage, a revoluble curved table pivoted on the sub-carriage at the rear of the platen-carriage, a gear on the axis of the table, and driving gearing on the sub-carriage, intermediate the platen-carriage and said first-mentioned gear, for rotating the table against the web to free the carbon-sheets 70 from the platen, said driving gearing comprising a pinion in mesh with the first-mentioned gear, a rack in mesh with the pinion, and means for swinging the rack.
- 75 21. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revoluble upon an axis intermediate the ends thereof on the sub-carriage at the rear of the machine, and means for rotating the table from a lower inverted 80 concave position to an upper convex position against the web to draw the carbon-sheets clear of the platen.
- 85 22. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revoluble upon an axis intermediate the ends thereof on the sub-carriage at the rear of the machine, means for rotating the table from a lower inverted concave position to an upper convex 90 position against the web to draw the carbon-sheets clear of the platen, and spokes for supporting the table on its axis.
- 95 23. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revoluble upon an axis intermediate the ends thereof on the sub-carriage at the rear of the machine, means for rotating the table from a lower inverted concave position to an upper convex 100 position against the web to draw the carbon-sheets clear of the platen, spokes for supporting the table on its axis.
- 105 24. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revoluble upon an axis intermediate the ends thereof on the sub-carriage at the rear of the machine, means for rotating the table from a lower inverted concave position to an upper convex 110 position against the web to draw the carbon-sheets clear of the platen, spokes for supporting the table on its axis, and a stop-pin on one of the spokes for engagement with the sub-carriage to determine the carbon-releasing position of the table.
- 115 25. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revoluble upon an axis intermediate the ends thereof on the sub-carriage at the rear of the machine, means for rotating the table from a lower inverted concave position to an upper convex 120 position against the web to draw the carbon-sheets clear of the platen, spokes for supporting the table on its axis, and a stop-pin on one of the spokes for engagement with the sub-carriage to determine the carbon-releasing position of the table.

hind the platen-carriage for rotation against the web, to draw the carbon-sheets clear of the platen to condition the web for a relative shift of the carbon-sheets and work-sheets, and a roller on the rear end of the table, when the table is in normal or typing position, for frictionless engagement with the web to draw out the web to lay the latter on the table when the table is rotated to release the carbon-sheets from the platen.

9. In a continuous billing typewriting machine, the combination of a carriage, a platen on the carriage, around which a composite web comprising plies of work-sheets may be fed with interleaved carbon-sheets, a sub-carriage to travel with the platen-carriage, and a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, the table, when in normal or typing position, being inverted to present a concavity in which a slack may be formed in the web.

10. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, the table, when in normal or typing position, being inverted to present a concavity in which a slack may be formed in the web, and means for directing the web over the end of the inverted table.

11. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, the table, when in normal or typing position, being inverted to present a concavity in which a slack may be formed in the web, and means for supporting the slack in the web at its rear on the table, and at its front clear of the table.

12. In a continuous billing typewriting machine, the combination of a carriage, a platen on the carriage, around which a composite web comprising plies of work-sheets

may be fed with interleaved carbon-sheets, a sub-carriage to travel with the platen-carriage, a revolute curved table pivoted at an intermediate point thereof to the sub-carriage behind the platen-carriage for rotation against the web, to draw the carbon-sheets clear of the platen to condition the web for a relative shift of the carbon-sheets and work-sheets, the table, when in normal or typing position, being inverted to present a concavity in which a slack may be formed in the web, and means for supporting the slack in the web at its rear on the table, and at its front clear of the table, such slack-supporting means comprising a pair of rollers.

13. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute, invertible, concavo-convex table pivoted upon the sub-carriage and having a normal or typing position in which a slack in the web hangs in the concavity of the table, means for rotating the convex surface of the table against the web to draw the carbon-sheets free of the platen and eliminate the slack in the web, a platform for the machine, and means for supporting the revolute table entirely above the platform.

14. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute, invertible, concavo-convex table pivoted upon the sub-carriage and having a normal or typing position in which a slack in the web hangs in the concavity of the table, means for rotating the convex surface of the table against the web to draw the carbon-sheets free of the platen and eliminate the slack in the web, and means for supporting the revolute table at an intermediate point thereof entirely above the platform.

15. In a continuous billing typewriting machine, the combination of a carriage, a platen on the carriage, around which a composite web comprising plies of work-sheets may be fed with interleaved carbon-sheets, a sub-carriage to travel with the platen-carriage, a revolute, invertible, concavo-convex table pivoted upon the sub-carriage and having a normal or typing position in which a slack in the web hangs in the concavity of the table, means for rotating the convex surface of the table against the web to draw the carbon-sheets free of the platen and eliminate the slack in the web, a platform for the machine, means for supporting the

- machine, the combination of a carriage, a platen on the carriage, around which a composite web comprising plies of work-sheets may be fed with interleaved carbon-sheets, 5 a sub-carriage to travel with the platen-carriage, a curved table revolute upon an axis intermediate the ends thereof on the sub-carriage at the rear of the machine, means for rotating the table from a lower inverted 10 concave position to an upper convex position against the web to draw the carbon-sheets clear of the platen, spokes for supporting the table on its axis, and a stop-pin on the sub-carriage for engagement with one 15 of the spokes to determine the normal or typing position of the table.
25. In a continuous billing typewriting machine, the combination of a carriage, a platen on the carriage, around which a composite web comprising plies of work-sheets 20 may be fed with interleaved carbon-sheets, a sub-carriage to travel with the platen-carriage, a curved table revolute upon an axis intermediate the ends thereof on the sub- 25 carriage at the rear of the machine, means for rotating the table from a lower inverted concave position to an upper convex position against the web to draw the carbon-sheets clear of the platen, and a platform for the 30 machine which extends horizontally under the table in the normal or typing position of the latter.
26. In a continuous billing typewriting machine, the combination of a carriage, a platen on the carriage, around which a composite web comprising plies of work-sheets 35 may be fed with interleaved carbon-sheets, a sub-carriage to travel with the platen-carriage, a curved table revolute upon an axis 40 intermediate the ends thereof on the sub-carriage at the rear of the machine, means for rotating the table from a lower inverted concave position to an upper convex position 45 against the web to draw the carbon-sheets clear of the platen, a platform for the machine which extends horizontally under the table in the normal or typing posi-

tion of the latter, and means for supporting the sub-carriage on the platform at the rear of the table for movement on the platform in letter-feed and return directions with the platen-carriage. 50

27. In a continuous billing typewriting machine, the combination of a carriage, a platen on the carriage, around which a composite web comprising plies of work-sheets may be fed with interleaved carbon-sheets, a sub-carriage to travel with the platen-carriage, a curved table revolute upon an axis intermediate the ends thereof on the sub-carriage at the rear of the machine, and means within the table for rotating the table from a lower inverted concave position to an upper convex position against the web to draw the carbon-sheets clear of the 60 platen. 65

28. In a continuous billing typewriting machine, the combination of a carriage, a platen on the carriage, around which a composite web comprising plies of work-sheets 70 may be fed with interleaved carbon-sheets, a sub-carriage to travel with the platen-carriage, a curved table revolute upon an axis intermediate the ends thereof on the sub-carriage at the rear of the machine, and 75 means within the table on the sub-carriage for rotating the table from a lower inverted concave position to an upper convex position against the web to draw the carbon-sheets clear of the platen. 80

29. In a continuous billing typewriting machine, the combination of a carriage, a platen on said carriage around which a composite web comprising plies of work-sheets may be fed with interleaved carbon-sheets, a sub-carriage to travel with said carriage, and means to so condition the web that there may be effected a relative shifting between the carbon-sheets and the work-sheets, said means comprising a revolute curved table 85 pivoted at its axis on said sub-carriage, and a handle to rotate said table from an ineffective position to an effective position. 90

JOHN WALDHEIM.
